UNITED STATES PATENT OFFICE.

EDWARD BERNARD HESS AND LEWIS CARY MYERS, OF BROOKLYN, NEW YORK,
ASSIGNORS TO ROYAL TYPEWRITER COMPANY, INC., OF NEW YORK, N. Y.

TYPEWRITING MACHINE.

1,417,904.

Specification of Letters Patent. Patented May 30, 1922.

Original application filed January 13, 1921, Serial No. 436,924. Divided and this application filed May 27, 1921. Serial No. 478,164.

To all whom it may concern:

Be it known that we, EDWARD BERNARD HESS and LEWIS CARY MYERS, both citizens of the United States, residing in Brooklyn, county of Kings, city and State of New York, have invented certain new and useful Improvements in Typewriting Machines, of which the following is a specification.

The application for this patent is a division of our application for patent filed January 13, 1921 No. 436,924. That application shows all the mechanism of a complete typewriting machine. The invention claimed herein relates particularly to a novel arrangement of certain parts of the mechanism of the typewriting machine whereby it is simplified and made small, compact, light and portable, but strong and durable, and whereby writing in such small machine may be at all times plainly visible.

In carrying out our invention we employ sheet metal and drawn stock to a very large extent in the construction of the machine, in order to make the mechanism both strong and durable, as well as light and compact. We use the full number of keys in the key board, arranged in four banks, as in most standard machines. Efficient mechanism is provided for shifting and locking the platen for upper and lower case printing.

Inasmuch as the height of the new machine is considerably less than that of the standard Royal machine, the printing point on the platen has been placed considerably above a horizontal line drawn through the axis of the platen and the type segment has been inclined rearwardly and arranged obliquely with reference to the horizontal plane of the machine in order that the line of print may be properly presented to the eyes of the operator. This involves a new arrangement of the mechanism for connecting the key levers to the type bars in order that the latter may be properly moved from their points of rest to the printing point.

As in the Royal machine, we employ a unitary platen carriage system and the general construction of the margin rail, center stop, escapement and ribbon driving mechanism is similar, but the arrangement of some of these mechanisms has been some-

what changed. The platen carriage is so mounted and actuated that it moves in a plane oblique to the horizontal plane of the key levers, and the type bars are arranged in a fan-shaped field, i. e., the arc in which the inner ends of the type bars are pivoted is considerably smaller than the arc in which the type carrying ends of the type bars are disposed when at rest.

The construction and arrangement of the mechanism in the new machine is such that all interference of one part with another in the transmission of power from the finger keys to the type bars, which is an essential though a difficult feature in a compact, portable full-standard key board machine, is avoided.

The key levers are connected with the type bars by flexing connections which exert a tensile strain on the type bars and pull them to the printing point with increasing or accelerated velocity as they approach the printing point. These connections between the type bars and the key levers are made between the finger pieces where power is applied and the fulcra of the levers, and said levers are provided with extensions projecting rearwardly from the fulcra which engage a universal bar that controls the movement of the carriage. Thus the key levers when acting upon the universal bar are of the first order and when acting on the type bar mechanism are of the second order.

Inasmuch as the type bars in the new machine are operated by tensile strain only between the key levers and the type bars and as these connections are made in a novel way, the machine is not impaired in operation as is the case in machines where compression and lateral strain are present in such connections.

In the accompanying drawings:—

Figure 1 is a plan view of so much of a typewriting machine with our improvements applied as is necessary to illustrate certain features of our invention.

Figure 2 is a transverse section in front of the platen and the type bar segment.

Figure 3 is a longitudinal section of the machine looking towards the left-hand side thereof.

Figure 4 is a side elevation of the right-hand side of the machine with certain parts shown in dotted lines.

Figure 5 shows a vertical section of a part 5 of the machine looking towards the left.

Figure 6 is a view in longitudinal section showing portions of the mechanism for raising and lowering the carriage and for locking it in its adjusted position.

10 Figure 7 is a view of the same mechanism in section on the line 7-7 of Figure 6.

Figure 8 is a detail view in section on the line 8-8 of Figure 6.

15 Figure 9 is a detail view in section on the line 9-9 of Figure 6.

Figure 10 is a detail view in section on the line 10-10 of Figure 6.

20 Figure 11 is a rear view of parts of the mechanism at the rear of the machine, some parts being shown in section.

25 Figure 12 is a detail sectional view of the bracket which supports the worm shaft of the ribbon mechanism and some of the stops for limiting the vertical movements of the carriage.

The base frame A of the machine is made of a thin, light but stout and strong sheet metal. Separate front top plates A² are employed and they are secured in place at 30 a⁵. The frame serves as a base support for all of the mechanism and a casing for portions thereof. The top plates A² serve as a dust shed for parts of the mechanism.

35 The segment B to which the type bars C are pivoted is of cast metal and it may be here stated that this member is the only one in the machine which is cast, all other parts being of the lightest possible character. This part is made particularly strong and 40 rigid inasmuch as it sustains a large number of type bars which must be pivotally mounted in such manner as to be moved with the greatest accuracy and precision toward and from the printing point on the platen.

45 The segment serves to support other parts of the mechanism as will be hereinafter described.

It will be observed that the segment is arranged at an oblique angle to the horizontal, this angle being obtuse to the plane of the key levers, as indicated in Figure 3. The segment is formed with a curved rib b which provides a striking surface for the type bars intermediate their ends and ensures the impact of the type at the proper point without undue penetration of the material to be printed upon.

50 The type bars C are thin, light and strong, being made of sheet metal, preferably corrugated as indicated at c. Their inner ends are disposed in slots b' cut in the lower portion of the segment and they are pivoted to a curved rod or wire b² at the inner end of the slots.

55 The type carrying ends of the type bars

rest on a support C' suitably cushioned and so disposed as to normally hold the type bars at an obtuse angle to the plane of the segment, but in this case the arc of the support is materially greater than that of the 70 inner bearing points of the segment. In this way the pivoted ends of the bars may be brought close together while the outer ends thereof may be spread so that the type carrying ends of the bars may not interfere. 75 In this way also space is provided in the neighborhood of the segment for accommodating certain parts of the mechanism.

It will be observed that the front part of the machine between the top plates or dust sheds A² and in front of the support C' is closed by a bridge piece A³ which is attached to the front plates in the manner indicated at a¹⁰. The upper part of this bridge piece is curved in the manner shown and it has a 80 downwardly extending portion a¹¹ (Fig. 3) which reaches to the type bar support H and covers the mechanism immediately in rear of it. In this way the dust plates A² and the bridge piece A³ serve to protect to a very 85 large extent parts of the mechanism. It will be observed that the type heads are covered by the bridge piece A³ and furthermore that the curved middle portion of this bridge piece is below the top plates A² so that 90 the platen and parts immediately below it are distinctly visible.

It will be also observed that while the mechanism in the rear part of the machine is obliquely arranged, the parts in the front 100 of the machine, excepting the type bars, are shown arranged horizontally. The top plates A² are arranged in a true horizontal plane and the ribbon spools R whose shafts extend through the plates A² are arranged horizontally somewhat below the line of print and they lie above the top plates or dust sheds A².

The type bars C are normally held on their rest or are returned thereto by individual 110 springs c² attached to a flange c³ of the rest and to the type bars near their inner ends in front of and above their pivots.

The key board contains the standard number of type keys, viz, forty-two, arranged in 115 four rows or banks and it also contains keys K, K', K² for operating the carriage shift, back space and margin release mechanism. Each of the forty-two key levers E is of the first order fulcrumed on a common rod e, 120 its front portion being connected to a type bar between the fulcrum and the finger piece while the rear part of the lever is extended rearwardly from the fulcrum and operates on a universal bar F. Each key lever, therefore, when operating on the universal bar is of the first order, but when operating a type bar it is of the second order, inasmuch as at this time the weight is situated between the lever and the fulcrum. 125

The universal bar F is also operated by a space bar D¹⁰ carried by the front ends of levers d¹⁰ pivoted to the rod e and having extensions operating on the universal bar in the same manner as the type key levers. The rear portions of the levers d¹⁰ are connected by a tie bar d¹¹. A stop for the space bar is shown at d¹².

The heels c' of the type bars below and 10 behind their pivots are connected by links g to the rear ends of the short bent links G pivotally mounted on a common rod g' which is supported in a frame H. Each link G is connected by a link g² to a corresponding key lever E. In order that the levers G may be placed close together to economize space, the links are connected with the levers at different distances from their pivots, as shown in Figure 3. 15

20 The rear ends of the key levers move different distances, inasmuch as the levers are of different lengths. Therefore the rear ends of these levers are inclined at different angles and in such manner as to give to 25 the universal bar the same movement whichever key is operated.

The means described for connecting the key levers to the type bars affords a flexible connection between these members and 30 a tensile strain is imparted through the links g from the key levers to the type bars. Furthermore, the connections are such that the types approach the printing point with an accelerated movement, which is at first 35 comparatively slow when the keys are first touched and they rapidly increase in speed as the depression of the keys continues. Inasmuch as the platen is arranged in an obliquely disposed carriage and the printing point is above the horizontal plane of 40 the axis of the platen, the connections between the key levers and the type bars are such as to give the required movement to them.

45 The arrangement of the type bar operating devices is such as to procure substantially uniform depth of depression and approximately uniform "touch" of all the finger pieces of the key board. The shorter 50 key levers, whose finger pieces x' are in the rear row of the key board are each connected to one of the longer links G by a link y' extending upwardly from the corresponding key lever, the points of connection 55 of the link y' to the link G and to the key lever being such as to afford the desired extent of depression of the finger piece x' of the key lever to throw the corresponding type bar to the printing point. The next 60 longer key levers whose finger pieces x² are in the second row from the rear in the key board, are also each connected to a link G by a link y² but the point of connection of the latter link to the link G is nearer 65 the fixed axis about which the link G moves

than is the corresponding link connection of the shortest key lever. The relationship of the parts and leverages is such that the finger pieces x', x² of the two rear rows have the same extent of depression and the 70 same "touch." The next longer levers whose finger pieces x³ are disposed in the second row from the front of the key board are each connected to one of the shorter front links G as shown in Figure 3 by a 75 link y³. The distances from the axes of these shorter links G and from the axes of the corresponding key levers at which the connections of the vertical links are made are such as to afford a depth of depression 80 of the finger pieces, the same as that for the finger pieces x', x² in the two rear rows and also of substantially the same touch.

Each lever carrying a finger piece x⁴ in the front row of the key board is connected 85 to one of the shorter front links by a vertical link y⁴. The connection of the latter link to the front link G is nearer the fixed axis thereof than is the connection between the key levers of the third row and such 90 axis. The finger pieces x⁴ of the lower row in the key board have the same extent of depression as the others and substantially the same touch. As the front links G are made alternately long and short, the staggering of the ends of the links with reference to a straight, transverse line affords ample room for the hooks, by which the links g and y', y², y³, y⁴ are attached to the links G so that in the operation of the 100 machine one cannot interfere or collide with another. Each front link G is of elbow shape, its lower front end being bent upwards. The point of connection of the type bar link g to the corresponding link 105 G is thus made at a higher point than heretofore. In this way we are enabled to reduce to some extent the height of the machine and parts of the mechanism are made to so co-operate as to effect the full throw 110 of the type bars. Furthermore, the requisite clearances are obtained between moving and stationary parts.

The platen Z is mounted in a carriage, the side pieces L of which are shown in 115 the drawing. These sides are connected by a sheet metal rail l supported by a sheet metal carriage shift rail L' having downwardly extending legs l', (Figure 4), the lower ends of which are pivotally connected 120 with the front ends of links l², the rear ends of which are pivotally connected with the sides of the base frame of the machine. The front ends of the carriage lifting levers L² are pivotally connected with the shift rail at l⁴, while the rear ends of these levers are secured to a rock shaft l⁵ mounted to turn in the machine frame.

It will be observed that the carriage frame is arranged obliquely. The rails l, L' 130

have their opposite surfaces rearwardly and downwardly inclined at a slight angle and in order to adjust this angle, the pivots of the links l^2 are made adjustable as indicated in Fig. 8. As there shown, each link l^2 is connected by a screw l^6 to a sleeve or spacer l^7 and is free to turn thereon. The spacer extends through a slot l^8 in the side of the frame A and has a flattened portion l^9 therein. The spacer carries a nut l^{10} between which and the sides of the frame a washer l^{11} is interposed. Each of the links l^2 is mounted in this way and by these devices the inclination of the carriage may be adjusted. The rock shaft l^5 carries a rearwardly extending arm m connected with a vertically arranged coiled spring m' , attached to the lower portion of the base frame and which serves to, in a measure, counterbalance the weight of the carriage and to assist in elevating it. By the devices described, the carriage may be given adjustments by which the printing point of the platen may be slightly varied in order that the type bars may properly abut the ridge b on the segment and that the type may strike the platen at the proper point and with suitable force.

There are anti-friction ball bearings interposed between the rails l and L' of the kind commonly used in the Royal machine and the rails l , L' are held properly connected by guiding plates m^2 . The rails l , L' are made of light but tough and strong sheet metal, bent to the required shape.

In order to further support and guide the carriage, we provide a guide bar M^5 which is secured to the sides of the base frame in a machine and this bar co-operates with a roller m^3 and a pin m^4 carried by an arm m^5 projecting upwardly and forwardly from the frame N of the escapement mechanism.

In order to shift the platen carriage for upper and lower case printing, we employ a shift key K pivoted at o (Fig. 6) to a frame J in which the key levers are arranged. The lever K has an upwardly projecting arm o^5 connected by a link o' to the lower end of an arm o^2 extending downwardly from one of the lifting levers L^2 . The link o' is provided with adjusting devices o^3 by means of which its length may be changed and its front end is formed with a loop o^4 which engages a pin o^6 on the lever in order that the lever may have a slight movement before moving the rod and the lifting lever L^2 connected therewith. By depressing the finger piece K, the lever may be operated to elevate the carriage for upper case printing and hold it as long as the finger of the operator is held on the key. When it is desired to hold the carriage in an elevated position for printing a plurality of capitals, a lever O' may be depressed which serves to lock the carriage shift key.

The mechanism shown at O^2 for thus locking the shift key is of well known construction and need not be described in detail. Suffice it to say that when this key is depressed, it holds the carriage in upper case position until the shift key is operated to release it.

In order to lock the carriage in lower case position, we employ a latch P (Fig. 6) in the form of a bell crank lever of general L-shape. It is pivotally mounted at p and its upper end carries an arm p' which engages an ear l^{15} which projects forwardly from one of the legs l' of the carriage support. The latch P is normally inclined from its lower end upwardly and rearwardly and this upward, rearwardly extending portion of the lever is connected with a spring p^2 attached to the base frame. The latch P is connected by a link p^3 with the upper end of the arm o^5 of the lever K and when the shift lever is operated, the latch P is first released from the carriage and then the shift lever serves to raise the carriage to the desired extent. It will be observed that the link p^3 is connected to the latch in rear of its pivot and when the shift key is operated, the latch is turned quickly to release the carriage and before the shift key can operate. Furthermore, it will be seen that the latch is so located and mounted that its upper front portion does not at any time come in contact with the frame J in front of it. The lower portion of the lever K is provided with an extension o^{10} which projects through openings o^{11} in the frame J and the base frame of the machine. By this construction, the lever is guided in its movements.

The carriage is moved from right to left during the operation of printing in the usual way by a strap q connected to a spring drum Q housed in a suitable casing. The spring drum is carried by an arm q^3 on a bracket Q^4 secured to the left-hand side of the base frame and this bracket serves to support parts of the ribbon operating mechanism.

In order to control the transverse movement of the carriage, appropriate escape- ment mechanism is provided. T indicates a rack bar supported on arms t pivoted to the side plates of the carriage at t' . As the mechanism for releasing the rack bar from its operating pinion forms no part of the present invention, the detail of this mechanism is not illustrated. The pinion S with which the rack bar T engages is connected with a ratchet wheel S' controlled by escape- ment mechanism indicated at U, (Fig. 5) but inasmuch as this mechanism is similar to that in the standard Royal machine, it is not shown in detail and need not be further described except to say that by reference particularly to Figure 5 it will be observed

that the escapement mechanism is obliquely arranged in a manner similar to the arrangement of the type bar segment and the carriage release. It may be said, however, 5 that the escapement rocker u is pivotally mounted in a frame N . The rocker is operated by a lever T^2 pivoted at t^5 to an arm t^6 extending forwardly from a bar A' secured to the middle portion of the rear part 10 of the machine frame. The lever T^2 engages a roller t^7 on a downwardly extending spring arm t^{10} of the rocker. As the lever T^2 is oscillated, the rocker is correspondingly moved and operates the escapement mechanism. 15

The lever T^2 is operated by an arm f projecting from the universal bar F . The arm f of the universal bar is connected with the lever T^2 by a link f^4 , the length of which 20 may be varied by the devices f^5 . It will be observed that the universal bar is arranged horizontally or nearly so instead of vertically as in many prior constructions. In this way it is adapted to a frame of small 25 height or size and it is also adapted to be operated directly by the extensions of the key levers and the space levers. It will be observed that the key levers when operating on the universal bar are of the first order 30 and there is no mechanism interposed between the key levers and the universal bars. This affords a compact, small and efficient construction.

It will be observed that the frame N of 35 the escapement mechanism has a bracket n in which is mounted a set screw n' . This screw is adapted to engage the top of the flanged rear portion of the base frame when the carriage is returned after being raised. 40 The screw thus acts as a back stop for the carriage, arranged centrally of the machine, and this stop co-operates with other stops n^2, n^4 at the front of the machine. The stops n^2, n^3 on the right-hand side of the 45 machine are carried by a bracket w to which the back space lever is pivoted, while the stops n^4, n^5 of the left-hand side of the machine are carried by the bracket Q^4 which supports the spring drum and parts of the 50 ribbon mechanism. By these devices, the oblique movement of the carriage is accurately controlled. The set screws n^2, n^4 arrest the downward movement of the carriage by engaging the shift rail L' while the 55 screws n^3, n^5 arrest its upward movement, being arranged to abut against arms n^6 on the downwardly extending legs l' of the shift rail.

An arm N^2 extends from the escapement 60 frame N and projects downwardly and rearwardly therefrom, its lower end abutting against an adjusting screw N^3 . This arm is arranged longitudinally of the machine and as shown is formed integrally with the escapement frame N . The arm serves to

steady the carriage and prevent it from tilting or moving forwardly. It will be understood that the escapement frame N is connected with and supported by the lower shift rail L' , as shown in Figure 5. This 70 connection is similar to that in the Royal standard machine. Inasmuch as the carriage overhangs its front supports and as the carriage is a floating carriage being supported at the front by the shift rail which 75 is in turn supported by the swinging links and levers, there is a tendency for the carriage to sag, but by means of the brace arm N^2 in co-operation with the front supports of the carriage, this tendency is obviated as 80 by means of the set screw N^3 , a torsional strain can be imparted to the sub-frame of the carriage which will cause it to maintain its proper oblique arrangement without any material change. The set screw N^3 extends 85 through the back frame and through the tie plate A' as indicated in Fig. 5. In this way we provide what may be termed an aligning arm, which extends from the shift rail or carriage support to a rigid abutment. 90

The drawings show some of the mechanism of the typewriting machine which is not herein particularly described as it forms no part of the present invention, and some features of which are claimed in other co-pending applications. 95

The platen Z , it will be understood, co-operates with the paper table Z' which may be of any suitable kind. The ribbon R' passes from spool to spool R around guides 100 r past a type guide R^2 and may be suitably guided by a vibrator or other suitable ribbon guide V .

The drawings show, Fig. 1, a margin release key K^2 , but the mechanism connecting 105 this key with the margin release lever is not shown.

Figure 1 of the drawings also shows a handle K^5 for controlling the operation of the ribbon mechanism, which mechanism is 110 claimed in another co-pending application, but inasmuch as part of this mechanism is herein shown and inasmuch as part of the vibrator mechanism is also shown, it will be briefly described.

As shown in Figure 5, the vibrator V extends downwardly from the type guide and is pivotally connected at v with a bell crank lever 70 pivoted at 71 to the escapement frame N and having a downwardly extending arm 72 pivotally connected at 73 with a downwardly and rearwardly extending arm 74 , having a rear edge provided with two parts 75 and 76 adapted to engage a pin 77 carried by the lever T^2 , which as before explained is actuated by the universal bar. Each time that the universal bar is actuated the arm 74 is turned on its pivot 73 and correspondingly moves the bell crank lever 70 which in turn actuates the vibrator. The 120 125 130 135 140 145 150 155 160 165 170 175 180

lever 70 is pulled in one direction by a spring 70^a.

When a bichrome ribbon is used it is necessary to shift the vibrator so that it may 5 present only one color to the type while vibrating. For this purpose we provide a lever 80 which is connected in any suitable way with an arm 83 on a shaft 84 carrying a notched hub 85 engaging a pawl 86 pivoted 10 at 87 to an extension of the escapement frame and held in engagement with the hub by a spring 88. The hub has two notches 89 and 90, with either of which the pawl 86 is adapted to engage and the pawl may be 15 made to engage either of these notches by turning the lever 80 in the proper direction. The shaft 84 has an arm 91 to which is pivotally connected a link 92 pivotally connected at 93 with an arm 94 of the lever 74. By 20 these devices when the lever is shifted, either of the edges 75 or 76 may be presented to the pin 77 in such manner as to elevate or depress the vibrator and cause it to operate in either the front or bottom portion of the 25 ribbon, which as usual has one color at its upper portion and a different color at its lower portion.

The downward movement of the lever 70 is limited by a stop 79 and this lever is urged 30 toward its stop by a spring 70^a as shown in Fig. 5.

It will be observed that the ribbon vibrating mechanism and the bichrome mechanism is supported on the same frame N that supports the escapement mechanism and other parts of the machine.

The spring drum which is connected to the carriage by the strap q is geared as shown at 30 with a worm shaft 31 which is inclined 40 forwardly and upwardly, the worm 32 being geared to a shaft 33 with which the vertical shafts or the ribbon spools are connected. This mechanism is claimed in another co-pending application, but it will be observed 45 that the spool operating mechanism is supported from the bracket Q⁴ which also supports the spring drum and the stops n⁴, n⁵ before referred to.

In Figures 2 and 3 part of the ribbon 50 mechanism is shown. The worm shaft 31 is supported by a bell crank lever 35 pivoted at 36 and having an arm 37 which engages a cam lever 38 on a shaft 39 extending to the front of the machine where it is provided 55 with an operating handle K⁵. This mechanism is not claimed herein but it is claimed in a co-pending application.

Part of the back space mechanism is shown 60 in the drawings and may be briefly described. The back space lever 2 is pivoted at 3 to the bracket w and has an arm 4 engaging the laterally extending arm 5 of a bell crank lever 6, pivoted at 7 to an arm 8 on the bracket w. The upwardly extending arm of 65 the bell crank lever operates the back space

mechanism in the manner described in another co-pending application. This same bracket w which supports part of the back space mechanism also supports the stops n², n³ as clearly shown in Figure 11. 70

We claim as our invention:

1. In a typewriting machine, a base frame, a platen, its carriage, means for raising and lowering the carriage, escapement mechanism for the carriage, a frame in which it is 75 mounted, and a stop for limiting the downward movement of the carriage carried by the escapement frame and engaging the base frame in rear of the escapement mechanism.

2. In a typewriting machine, a base frame, 80 a platen, its carriage, means for raising and lowering the carriage, escapement mechanism for the carriage, a frame in which it is mounted, a stop for limiting the downward movement of the carriage carried by the escapement frame and engaging the base frame in rear of the escapement mechanism, a spring drum for moving the carriage transversely, a bracket in which the spring drum is supported, and stops for limiting the movement of the carriage carried by said bracket. 85

3. In a typewriting machine, a base frame, a platen, its carriage, means for raising and lowering the carriage, escapement mechanism for the carriage, a frame in which it is 95 mounted, a stop for limiting the downward movement of the carriage carried by the escapement frame and engaging the base frame in rear of the escapement mechanism, a bracket on the right-hand side of the machine, and stops carried by said bracket for 100 limiting the upward and downward movement of the carriage.

4. In a typewriting machine, a base frame, a platen, its carriage, means for raising and 105 lowering the carriage, escapement mechanism for the carriage, a frame in which it is mounted, a stop for limiting the downward movement of the carriage carried by the escapement frame and engaging the base 110 frame in rear of the escapement mechanism, a bracket on the right-hand side of the machine, stops carried by said bracket for limiting the upward and downward movement of the carriage and back-space mechanism 115 supported on said bracket.

5. In a typewriting machine, a base frame, a platen, its carriage, means for raising and lowering the carriage, escapement mechanism for the carriage, a frame in which it is 120 mounted, a stop for limiting the downward movement of the carriage carried by the escapement frame and engaging the base frame in rear of the escapement mechanism, a bracket on the right-hand side of the machine, stops carried by said bracket for 125 limiting the upward and downward movement of the carriage, and ribbon mechanism carried by said bracket.

6. In a typewriting machine the combi- 130

- nation with the carriage-shift rail of means for raising and lowering it, links pivotally connected with the carriage shift-rail, and pivotal connections between said links and
- 5 the machine frame comprising sleeves adjustable in the machine frame, and clamping nuts for holding the sleeves in their adjusted positions.
7. In a typewriting machine the combination with the shift-rail of means for raising and lowering it, a link pivotally connected with a leg of the shift-rail, a sleeve to which the link is pivotally connected and which is adjustable in a slot of the machine frame, and a clamping nut for holding the sleeve in its adjusted position.
8. In a typewriting machine, a keyboard having a plurality of banks of keys, a platen, a platen carriage, a shift frame having a track on which said carriage is mounted to travel, all of said parts being inclined rearwardly from the vertical, a type segment similarly inclined, type bars pivoted at their rear ends and inclined forwardly and upwardly, a front rest for said type bars holding them in a fan shape, parallel links supporting the shift frame, and means engaging one of said links for shifting the frame in an oblique direction upwardly and rearwardly.
- 20 9. In a typewriting machine, the combination of two main portions, a main frame and a shift frame; a carriage and escapement frame carried by the shift frame, the shift frame and associated parts being inclined rearwardly from the vertical with reference to the main frame, means for shifting the shift frame, brackets secured on opposite sides of the main frame below the carriage, adjustable stops carried thereby for limiting the movements of the shift frame, and a stop carried by the escapement frame and engaging the main frame when the shift frame is in normal position.
- 45 10. In a typewriting machine, a main frame, a platen having its printing point above a horizontal plane passing through its axis, a platen carriage, a shift frame for the carriage, said shift frame and associated parts being inclined rearwardly from the vertical, means for shifting said shift frame obliquely, a ribbon vibrator carried by the shift frame and lying parallel to the inclination of the shift frame, and ribbon spools mounted on vertical axes on the main frame and lying in a plane below the vibrator.
- 30 11. In a typewriting machine, a main frame, a platen having its printing point above a horizontal plane passing through its axis, a platen carriage, a shift frame for the carriage, said shift frame and associated parts being inclined rearwardly, a type segment on the main frame carrying a type guide, a ribbon vibrator carried by the shift frame and guided by the type guide,
- said parts lying parallel to the inclination of the shift frame, and ribbon spools mounted on vertical axes on the main frame and lying in a plane below said vibrator.
12. In a typewriting machine, a main frame, a platen carriage, an escapement mechanism frame, a shift frame supporting the carriage and escapement frame, said shift frame and associated parts being rearwardly inclined, an arm on the escapement frame having an oblique face, an adjustable stop on the main frame engaging said oblique face in all positions of the carriage, a stop on the escapement frame at the rear thereof engaging the main frame in the normal position of the shift frame, and stops carried by the front of the main frame for limiting the movements of the shift frame.
- 75 13. In a typewriting machine, a platen, a carriage in which it is mounted, escapement mechanism for the carriage, type-bars, pivoted key-levers having projections arranged in different horizontal planes in rear of their pivots for operating the escapement, and connections between the key-levers and the type-bars made between the finger pieces of the keys and the pivots of the levers.
- 25 14. In a typewriting machine, a platen, a carriage in which it is mounted, escapement, mechanism for the carriage, type-bars, pivoted key-levers having projections arranged in different horizontal planes in rear of their pivots for operating the escapement, and flexing connections between the key-levers and the type-bars made between the finger portions of the keys and the pivots of the levers.
- 30 15. In a typewriting machine, a platen, a carriage in which it is mounted, escapement mechanism for the carriage, type-bars, pivoted levers having projections arranged in different horizontal planes in rear of their pivots for operating the escapement, and accelerating connections between the key-levers and the type-bars made between the finger portions of the key-levers and the pivots of the levers.
- 40 16. In a typewriting machine, a platen, a carriage in which it is mounted, escapement mechanism for the carriage, pivoted key-levers having projections arranged in different horizontal planes in rear of their pivots for operating the escapement mechanism, flexing, accelerating link connections between the type-bars in rear of their pivots and the key-levers between their pivots and their finger pieces.
- 55 17. In a typewriting machine, a platen, a carriage in which it is mounted, escapement mechanism for the carriage, pivoted key levers of different lengths mounted on a common pivot rod, said key levers having extensions inclined at different angles in rear of their pivots for uniformly operating the

- escapement mechanism, and accelerating type-bar operating connections between the inner ends of the type bars and the key levers at points between their pivots and finger pieces, said connections varying relatively to the lengths of the key levers.
18. In a typewriting machine, a platen, a carriage in which it is mounted, escapement mechanism for the carriage, pivoted key-levers of different lengths having projections in rear of their pivots for operating the escapement mechanism, short front links extending downwardly and then upwardly and having link connections with the type-bars in rear of their pivots, and inclined links connecting different portions of the front links with the key-levers between their pivots and their finger pieces.
19. In a typewriting machine, a platen, a carriage in which it is mounted, escapement mechanism for the carriage, pivoted key-levers of different lengths but uniform depression mounted on a common pivot rod and having extensions in rear of their pivots of substantially the same length but lying in different horizontal planes for actuating the escapement mechanism, short front links, link connections from their lower rear ends to the type bars in the rear of their pivots, and inclined links connected to the key levers between their finger pieces and their pivots and connected to said front links at points varying with the lengths of the key levers.
20. In a typewriting machine, a platen, a carriage in which it is mounted, escapement mechanism for the carriage, pivoted key-levers having projections lying in different horizontal planes in rear of their pivots for operating the escapement mechanism, short front links of elbow-shape and of different lengths having link connections from their lower rear ends to the type-bars in rear of their pivots, and inclined links connecting the front links with the key-levers between their pivots and their finger pieces.
21. In a typewriting machine, a platen, a carriage in which it is mounted, escapement mechanism for the carriage, a horizontally arranged universal bar operatively connected with the escapement mechanism, type-bars and pivoted key-levers for operating them having extensions in rear of their pivots operating upon the universal bar, and which are downwardly inclined from their pivots at different angles.
22. In a typewriting machine, a platen, a carriage in which it is mounted, escapement mechanism for the carriage, a horizontally arranged universal bar operatively connected with the escapement mechanism, type-bars, pivoted key-levers for operating them having extensions in rear of the pivots operating on the universal bar and which are downwardly inclined from their pivots at different angles, and ribbon winding mechanism operated by the universal bar.
23. A typewriting machine, comprising type-bars pivoted at their rear ends and normally resting at their front ends, type-bar links connected to the heels of the type-bars and flexibly connected at their front ends to the rear ends of relatively short front links, key-levers pivoted intermediate their ends having link connections between their front portions and the middle portions of the front links, and a universal bar directly actuated by the rear ends of the key levers which lie in different horizontal planes.
24. In a typewriting machine, the combination of a platen arranged to be impinged at a point in a plane above its horizontal axis, means for moving the platen transversely, an obliquely arranged segment in a plane below that of the platen, a series of type bars pivotally arranged in the segment in a vertical plane in front of the platen, a series of horizontally arranged key levers below the type bars, a series of accelerating toggle connections arranged between the key levers and the type bars, and connections from the key levers extending upwardly and operatively connected to the accelerating toggle connections for actuating the type bars; the series of key levers and the series of accelerating toggle connections and the series of type bars all extending longitudinally of the machine.
- In testimony whereof, we have hereunto subscribed our names.

EDWARD BERNARD HESS.
LEWIS CARY MYERS.
